RADIO SIGNALING

James A. Spencer, Teaneck, and Richard E. Mathes, Westfield, N. J., assignors to Radio Corporation of America, a corporation of Delaware

Application August 15, 1936, Serial No. 96,162

4 Claims. (Cl. 250—8)

This invention relates to radio relaying and receiving systems.

One object of this invention is to provide a radio relaying system employing printer-transmitter apparatus in which received radio waves are utilized to actuate the printer apparatus without affecting closely associated transmitter apparatus. A further object is to provide a circuit arrangement having impedance-balanced branches associated with a demodulating system for ultra short waves, which balanced circuit arrangement is effective to actuate printer mechanism, but during such actuation is ineffective to operate a closely associated transmitting device. It is a further object, however, to arrange this transmitting device so that it may be utilized at times for transmitting an independent signal to another receiver in the relay system.

Further objects, advantages and features of the present invention will be apparent from a consideration of the accompanying drawing, taken together with the following more detailed specification.

The accompanying drawing illustrates in wiring diagram form a preferred modification of our radio receiving and retransmitting system.

Turning to the drawing, modulated short wave signals received upon antenna A are fed into a radio receiver RR whose detected output is fed into a tone filter TF. The received tones are fed through a transformer T into a vacuum tube amplifier VA. The output of the amplifier is fed to a second transformer T2 across the plates 2, 4 of a combined amplifier-detector tube 6. To smooth out the rectified tone, a filter F, consisting of a resistance and condenser in-parallel, is provided. The output of the rectifier is then impressed upon the grid 8, as indicated, causing amplified, rectified current to flow to the plate 10 of the combined detector, direct current amplifier tube 6. This amplified current flows through the resistors 12, 14 which form a series connection between the cathode 16 of tube 6 and ground.

In the absence of signal current passes to plate 10 of tube 6 since the grid 8 is at the potential of cathode 16. Consequently, current flows to the plate 10 and through resistors 12, 14. As a consequence, the control grids 20, 22 of tubes 24, 26 become positive and both tubes 24, 26 pass plate current. Plate current flow through tube 24 flows through resistors 28, 30 and 32, thereby impressing a negative potential on the grid 34 of tube 36 with respect to the cathode 38 of that tube. As a result of this action, plate current flows through tube 26, whereas tube 36 is cut off.

The plate current of tube 26 flowing through coil 40 opens the contacts 42 of polar-relay 40, 42, 44, in turn breaking the circuit through the combined printer-transmitter apparatus 46, which is normally supplied with operating current from the lead 48.

In the presence of a signal upon antenna A, the resulting tone passed on to the rectifier tube 6 cuts off current to the anode 10 of the rectifier-amplifier tube 6. The blocking of tube 6 cuts off current flow through the resistors 12, 14 whereby the grid 20 of tube 24 is at ground potential. However, since current is flowing through resistance 32, the cathode 50 of tube 24 is at such a positive potential with respect to ground that tube 24 blocks. This action raises the potential of grid 34 with respect to its cathode 38 of tube 36, causing current flow through tube 36 and hence through coil 44. Simultaneously, while this action is going on, tube 26 blocks for the reason that current flow through the resistors 30, 32 has simultaneously held the potential of cathode 52 at positive potential with respect to ground, cutting off tube 26.

Cessation of current flow through coil 40 and actuating current flow through coil 44 thereupon closes contacts 42 and permits current to flow through the printer mechanism 46. In this way, the printer 46 is actuated by the incoming signals received upon antenna A without affecting in any way the transmitting contact TC. The reason for this is that the contacts TC are the contacts of a polar-relay having impedance-balanced coil sections 54, 56 through which current changes equally when contacts 42 are opened and closed. Equal changes through the coil sections 54, 56 do not affect the transmitting contacts TC.

However, when the transmitting contacts TC are opened and closed, and the transmitter section of the apparatus 46 is actuated, the cathodes 58, 60 of tubes 62, 64 are combined in potential with respect to the grids of tubes 62, 64 which, as indicated, are maintained at ground potential and supplied with tone from a tone transformer 66. With the contacts TC closed, the cathodes 58, 60 of tubes 62, 64 are combined in potential with respect to the grids of tubes 62, 64 which, as indicated, are maintained at ground potential and supplied with tone from a tone transformer 66. With the contacts TC closed, the cathodes 58, 60 of tubes 62, 64 are combined in potential with respect to the grids of tubes 62, 64 which, as indicated, are maintained at ground potential and supplied with tone from a tone transformer 66. This tone is then fed through a filter 70 to modulate waves generated in a radio transmitter 72, which modulated waves are then radiated over the transmitting antenna TA to any suitable receiving station.

When the contacts TC are open, cathodes 58, 55

60 of tubes 62, 64 assume a relatively high positive potential with respect to ground, as a consequence of which tubes 62, 64 block and no tone is impressed upon the radio transmitter 72.

5 The printer-transmitter 46 is preferably of the type known to the art as the "Teletype model 14".

It is to be noted that the printer-transmitter apparatus 46 may be connected at some distant point through the intermediary of a suitable landline (not shown), in which case separate positive supply voltages may be supplied at the points marked Y, Y. It is to be understood that this system may be used as part of a radio repeating system or as a link between a radio receiving station and a landline system, it being noted that the printer-transmitter apparatus 46 may be replaced by several printer transmitters connected in series.

Power supply for the various tubes involved 20 may be derived from the power supply circuits PS which are believed to be self-explanatory, it being noted that the heaters of the various tubes are connected to the points marked X, X.

For transmitting purposes, the tone filtered 25 through filter 70 may be rectified and used to key the transmitter 72 or it may be used to tone modulate radio waves generated at the transmitter 72.

What is claimed is:

30 1. In combination, means for receiving a keyed and tone-modulated code signal, means for demodulating the signal so as to obtain the keyed marking and spacing components thereof, a push-pull circuit operable under control of the keyed components of said signals, a polarized relay 35 symmetrically disposed in said push-pull circuit, a circuit having impedance-balanced branches and including the coils of a second polarized relay and contacts operative by the first said relay, transmitting contacts operative by the second said relay, a telegraph printer and keyer in one of said branches, radio transmitting apparatus connected to said transmitting contacts, and means including further circuit arrangements such that said telegraph printer is caused to respond to code signals as received, demodulated, and impressed upon

both of said relays, while said transmitting contacts remain undisturbed, and said radio transmitting apparatus is caused to respond only to keying operations initiated by said telegraph keyer for sending code signals through said second relay and the transmitting contacts thereof.

2. Radio telegraph apparatus comprising separate transmitting and receiving channels and a telegraph instrument having a receiving and keying circuit common to both channels, in combination with means including a push-pull electron tube circuit responsive to received code signals for causing said instrument to record the intelligence of said code signals while maintaining 10 said transmitting channel idle, and means including a polarized relay in a circuit having impedance-balanced branches, one of which contains said instrument for causing code signals to be sent out over said transmitting channel under 15 control of said instrument.

3. Apparatus in accordance with claim 2 and including means for demodulating the received code signals when they consist of tone-modulated signaling elements, and means for applying tone 20 modulation to the transmitted signals when they are keyed by said telegraph instrument.

4. Radio telegraph apparatus comprising separate transmitting and receiving channels and a typewriting telegraph unit having a receiving 30 and keying circuit common to both channels, in combination with a tone frequency potential source, a push-pull amplifier the bias of which is adapted to be varied by keying from full cut-off to a normal amplifying condition thereby to 35 transmit code signals modulated by said tone source, an electro-magnetic relay operable by said typewriting telegraph unit to control the bias on said amplifier, and means including a polarized relay under control of received code signals for 40 rendering said typewriting telegraph unit responsive without influencing said amplifier and its associated transmitting channel.
